BOX AND HANDLE THEREFOR

Raymond A. Bruner, Muncie, Ind., assignor to
 General Motors Corporation, Detroit, Mich., a
 corporation of Delaware

Application October 16, 1942, Serial No. 462,250

1 Claim. (Cl. 16—114)

This invention relates to containers with detachable handles and particularly to containers for storage batteries. It is an object of the invention to provide a container with handles so constructed that the handles may be attached without the use of screws or any other fastening means for ordinary handling.

Further objects and advantages of the present invention will be apparent from the following description, reference being had to the accompanying drawing wherein a preferred embodiment of the present invention is clearly shown.

In the drawing:

Fig. 1 is a plan view showing the fragment of an end wall of a storage battery box and a handle therefor constructed in accordance with the present invention.

Fig. 2 is a side elevation of a fragment of a battery box wall and handle attached thereto.

Figs. 3 and 4 are sectional views showing the manner of attaching the handle.

The end wall 10 is provided with a rectangular lug 11 extending from the top surface thereof and with a recess 12 defined by a vertical surface 13 and by a surface 14 slightly inclined from the horizontal. Numeral 15 designates in its entirety a handle formed of sheet metal and comprising a flat plate 16 having at its lower end a flange 17 adapted to be received by the recess 12 and having a flange 18 provided with a rectangular opening 19 slightly larger than the rectangular lug 11. The metal for the flange 18 is provided by shearing and bending a portion of the plate 16 away from the plane thereof, thus leaving an opening 20 through which a hand may extend so as to engage a grip portion 21 of C-shaped cross sectional contour as viewed in Figs. 3 and 4. The portion 22 of handle 21 has been formed of material of the plate 16 by shearing and bending it, thus providing for a portion of the opening 20.

The handle is applied to the end wall 10 by placing the flange 18 around the lug 11 as shown in Fig. 3. Then the plate 16 is forced toward the end wall to cause the flange 17 to enter the recess 12 as shown in Fig. 4. When the plate 16 has been forced into the position shown in Fig. 4, the flange 17 will have been forced into bending engagement with the surface 14 of recess 12, thus locking the handle 15 on the end

wall 10 with yielding pressure. The binding engagement of the handle 15 upon the end wall 10 provided by the coaction of flanges 17 and 18 is sufficient to prevent accidental movement 5 of the handle from the position shown in Fig. 4 to that shown in Fig. 3. The handle 15 can be removed by prying the plate 16 away from the box 10. The other end wall (not shown) of the box is formed like wall 10 to provide a lug 11 and a recess 12 for receiving a handle 15. Ordinarily the battery is transported by manually grasping the two handles 15. For such ordinary handling of the battery, the handles 15 remain in engagement with the box as shown in 10 Fig. 4. If the battery is to be hoisted by a single cable or chain and branch chains respectively connected with the handles causing the application of forces to the handles having substantial horizontal components tending to move 15 the handles into the position shown in Fig. 3, additional resistance to such movement may be provided by forcing flange 18 into the position 18A (Fig. 4) against the top of end wall 10. If the said horizontal force components are unusually large, it may be necessary to fasten the plate 16 to the wall 10 by a screw which will pass through a plain hole 25 and be received 20 by a tapped hole in the wall 10.

While the embodiment of the present invention as herein disclosed constitutes a preferred form, it is to be understood that other forms might be adopted, all coming within the scope 25 of the claim which follows.

What is claimed is as follows:

35. In combination with a molded box having a shoulder extending in a plane parallel to the top of the box and including a lug on the top of the box and on the same side thereof as said shoulder; a readily attachable and detachable 40 handle having an apertured flange adapted to fit over said lug and a second flange for engaging the shoulder, said two flanges being angled so as to diverge with respect to one another so that the first flange can be positioned over said lug 45 before the second flange engages the shoulder, said first flange holding the second flange from slipping off the shoulder when in engagement therewith when the box is being lifted by a vertical pull on said handle.
